UNITED STATES PATENT OFFICE.

JOSEPH G. LINDSAY, OF BARTLESVILLE, OKLAHOMA.

WELL-PACKING.

1,246,957.

Specification of Letters Patent. Patented Nov. 20, 1917.

Application filed March 26, 1917. Serial No. 157,513.

To all whom it may concern:

Be it known that I, JOSEPH G. LINDSAY, a citizen of the United States, residing at Bartlesville, in the county of Washington 5 and State of Oklahoma, have invented certain new and useful Improvements in Well-Packings; and I do declare the following to be a full, clear, and exact description of the invention, such as will enable others skilled 10 in the art to which it appertains to make and use the same.

My invention relates to devices for establishing a fluid tight contact between numerous kinds of well casings and the wall of the 15 well, the device being designed primarily for use in gas and oil wells, although it could well be employed in Artesian wells and the like.

The object of the invention is to provide 20 an extremely simple yet a highly efficient packing of the class specified which is automatically expanded in the well by continuing to drive the casing downwardly after the lower end thereof abuts the bottom of 25 the well or is otherwise held against further downward movement.

With the foregoing general object in view, the invention resides in certain novel features of construction and unique combinations 30 of parts to be hereinafter fully described and claimed, the descriptive matter being supplemented by the accompanying drawing which constitutes a part of this application and in which:

35 Figure 1 is a vertical section of a portion of a metal well casing equipped with the improved packing means, showing the relation of parts when the casing is inserted into the well;

40 Fig. 2 is a similar view after the packing is expanded.

In the drawing above briefly described the numerals 1 and 2 designate respectively upper and lower pipe sections, both of which 45 may, if desired, be formed of a number of short lengths of pipe connected by threaded collars 3 such as shown at the upper end of Figs. 1 and 2. In the embodiment illustrated, however, the section 2 is formed of 50 one piece of piping and may be of any preferred length.

A metallic sleeve 4 is threaded into the upper end of the pipe section 2 and extends above the same to form a continuation thereof, said sleeve having an external in-

tegral collar 5 abutting the upper end of the pipe section 2 and having above this collar an auxiliary collar 6 of less thickness. The lower end of the pipe section 1 slides through the sleeve 4 and is flared outwardly at 7 to prevent withdrawal therefrom and to maintain a pressure seated packing ring 8 in proper position for contact with the lower end of the sleeve.

A tapered packing sleeve 9 of rubber or 60 any other suitable flexible material surrounds the projecting upper end of the sleeve 4 and is formed with an internal groove receiving the collar 6, whereby said sleeve is held in operative position. The 65 sleeve 9 extends a considerable distance above the sleeve 4 and snugly surrounds the lower portion of the upper pipe section 1, the upper end of said sleeve 9 being internally chamfered at 10. 75

Another packing sleeve 11 which is tapered toward its lower end surrounds the pipe section 1 above the sleeve 9 and is carried by the collar 3, said sleeve 11 being adapted to be forced into said sleeve 9 to 80 expand the latter into approximate contact with the wall of the well. Downward driving of the upper pipe section 1, is then adapted to expand sleeve 11 as shown in Fig. 2 so that the rubber sleeve 9 is forced 85 into fluid tight contact with the wall of the well. To permit sleeve 11 to operate in this manner, it is formed of lead or other soft inelastic malleable metal, the lower end of said sleeve being provided with a binding 90 ring 12 of steel or the like slidably surrounding the section 1 immediately above sleeve 9. When section 1 is driven downwardly, after the section 2 has been brought to a standstill, the ring 12 and sleeve 11 95 expand the elastic sleeve 9 and said ring 12 comes into contact with the upper end of the sleeve 4. Further downward driving of the upper pipe section will now cause the sleeve 11 to buckle outwardly, as shown in 100 Fig. 2 and sleeve 9 is thus further expanded to form the required fluid tight packing.

I am aware that numerous packings have heretofore been provided which are operated by driving the well casing downwardly but 100 in so far as I am advised, a packing sleeve or tube formed of lead or similar material to operate as described, is novel. It is this device that constitutes the principal feature of the present invention and it will be 110

understood that its form may be varied as occasion may demand within the scope of the appended claim.

I claim:

- 5 In a well packer, the combination of an upper and a lower pipe section, a flexible packing sleeve carried by one section, and a second packing sleeve carried by the other section and adapted to enter said flexible sleeve, said second sleeve being formed of malleable non-elastic material and being
- 10

adapted to strike said one section and expand when the two sections are driven one toward the other.

In testimony whereof I have hereunto set 15 my hand in the presence of two subscribing witnesses.

JOSEPH G. LINDSAY.
